UNITED STATES PATENT OFFICE.

CHARLES ARTHUR SPEAKMAN, OF NEW YORK, N. Y., ASSIGNOR TO THE AMERICAN LITHOGRAPHIC COMPANY, OF SAME PLACE.

DESIGN FOR A PRINT OR PATTERN FOR CIGAR-BOXES.

SPECIFICATION forming part of Design No. 28,521, dated May 3, 1898.

Application filed March 2, 1898. Serial No. 672,334. Term of patent 7 years.

To all whom it may concern:

Be it known that I, CHARLES ARTHUR SPEAKMAN, a citizen of the United States, residing at New York city, in the county of New York and State of New York, have invented and produced a new and original Design for an Ornamental Print or Pattern for Cigar-Boxes, of which the following is a specification, reference being had to the accompanying drawing, forming a part thereof.

My design is intended for the ornamentation of a cigar-box.

In the accompanying drawing the design is shown on the lid or cover of a cigar-box, the view being a front elevation with the lid raised.

The design comprises a central horizontal panel A, having a border decorated with figures of tobacco-plants and surmounted by an eagle with spread wings having a shield in background and sprays of laurel; a scroll B above said panel, having convoluted ends

with streamers; a lower panel C, having midway of its length in background a shield containing the figure of a tobacco-plant; a landscape and marine view between the central and lower panels, showing a field of growing plants, a harbor, and fort, and two medallions D, flanking the lower panel and arranged under the central panel suspended from upright staffs assembled and terminating in a trident-shaped figure at each end, passing back of the central panel and through the convoluted ends of the scroll B.

I claim—

The design for an ornamental print or pattern for cigar-boxes substantially as shown and described.

In testimony whereof I affix my signature in presence of two witnesses.

CHARLES ARTHUR SPEAKMAN.
